Carpentier & Pitts.

UNITED STATES PATENT OFFICE.

HARRY R. COREY, OF BROOKLYN, NEW YORK, ASSIGNOR TO AMERICAN CAN COMPANY, OF NEW YORK, N. Y., A CORPORATION OF NEW JERSEY.

DESIGN FOR A TALCUM-POWDER BOX.

58,072.

Specification for Design.

Patented June 7, 1921.

Application filed June 30, 1919. Serial No. 307,854. Term of patent 14 years.

To all whom it may concern:

Be it known that I, HARRY R. COREY, a citizen of the United States, residing at Brooklyn, in the county of Kings and State of New York, have invented a new, original, and ornamental Design for Talcum-Powder Boxes, of which the following is a specification, reference being had to the accompanying drawing forming a part thereof.

On the drawing,

Figure 1 is an elevational view of a box embodying the design; and

Fig. 2 is a top plan view of the same.

My design is characterized by a diamond formation of the box, said diamonds having

rounded corners, and especially by a tapering of the body of the box to the top, whereby the top diamond configuration is materially smaller than the bottom diamond configuration, giving the appearance shown in my Fig. 2 when the box is viewed from the top.

I claim:

The ornamental design for a talcum powder box, as shown.

HARRY R. COREY.
